Rochester, N. Y., a corporation of New York

Application July 24, 1939, Serial No. 286,080

9 Claims. (CL. 125—11)

The present invention relates to mechanism for dressing grinding wheels.

A primary purpose of the invention is to provide a dressing mechanism that can readily be 5 adapted to dress a grinding wheel to any desired profile shape.

A further object of the invention is to provide an attachment for a known type of dressing mechanism which will allow that dressing mechanism to be used to dress an infinite variety of 10 profile shapes by making a simple adjustment and which will obviate the present necessity of employing different formers or guides for every change in profile curvature to be dressed.

15 Other objects of the invention will be apparent hereinafter from the specification and from the recital of the appended claims.

The invention has various applications. In the drawings, however, we have shown it applied to 20 the dressing mechanism of a Jones & Lamson thread grinding machine.

The dressing mechanism of such a machine is accurate, precise and entirely satisfactory within 25 its range. The profile shapes which can be dressed with this mechanism, however, as heretofore built, are determined by the formers or guide plates employed in the mechanism. For dressing straight profile shapes, straight-sided guides are used. For dressing curved profile shapes, curved 30 guides are employed, but separate guide plates are required for each shape to be dressed. Moreover, if a guide plate having a guide surface of a particular curvature does not prove in practice to be satisfactory for a particular job, it is necessary 35 to regrind the plate to a different curvature or to make a new plate. We have devised a simple and inexpensive attachment for adapting this dressing mechanism to the dressing of grinding wheels of a wide variety of profile curvatures 40 while using a standard straight-sided guide member.

In the Jones & Lamson dressing mechanism, a pair of diamonds are provided for dressing opposite sides of a disc-type grinding wheel. Each diamond is mounted in a reciprocable plunger for movement laterally of the wheel axis. The two plungers are operated by rocker arms and both the plungers and the rocker arms are mounted in a drum that is movable rectilinearly in a direction radial of the wheel axis. Each rocker arm carries a roller that engages a guide plate that has a straight guide surface inclined to the path of movement of the drum. The guide plates are movable relative to the drum and the guide surfaces of the two plates are inclined to

one another in accordance with the included angle between the active side surface of the grinding wheel which is to be dressed.

When the drum is actuated, it moves the diamonds in the general direction of the height of the wheel profiles and as the drum moves, the rollers carried by the rocker arms roll along the guide plates, rocking the rocker arms to move the diamonds laterally in a plane perpendicular to the central plane of the grinding wheel. The amount of lateral movement of each diamond is exactly proportional to the rectilinear displacement of the guide plates. Hence, the movement of each diamond is along an oblique straight line and diamonds, therefore, will dress straight line surfaces on the grinding wheel inclined to the plane of rotation of the wheel.

The present invention permits the dressing mechanism described to be used with but slight modification thereof to dress any curved profile 20 shape desired. To this end, we retain the straight guide plates of the described mechanism but provide means, such as an eccentric or cam, for moving these plates at a variable velocity. In this way, the amount of lateral movement of the diamonds is varied and hence is no longer in proportion to the rectilinear movement of the drum. The diamonds therefore no longer dress straight profile shapes on the grinding wheel but curved profile shapes, the amount of whose curvature 25 depends upon the variation in rate of movement of the guides. The eccentric, which controls the movement of the guides, is preferably constructed so that the amount of its eccentricity or throw is adjustable. Hence, by adjusting the eccentric, 30 varying amounts of curvature may be dressed on the wheel. Moreover, rotary cams can be substituted for the eccentric and a still wider range of profile shapes obtained.

In the preferred construction, a single eccentric or cam is employed to control the lateral movements of the two diamonds and preferably this eccentric or cam is driven through gearing actuated by the relative motions between the parts of the mechanism itself.

In the drawings:

Fig. 1 is a more or less diagrammatic perspective view showing the application of a preferred embodiment of the present invention to a dressing mechanism of the Jones & Lamson type and 50 illustrating the mode of operation of the modified dressing mechanism in the dressing of a grinding wheel;

Fig. 2 is a vertical sectional view through the drum that carries the dressing mechanism;

Fig. 3 is a fragmentary plan view of the drum with parts broken away;

Fig. 4 is a transverse sectional view taken through the forward at the end of the drum and showing particularly the dressing diamonds;

Fig. 5 is a transverse sectional view through the drum taken at a point to show the operative relation between the guide plates and the rocker arms;

Fig. 6 is a fragmentary view on an enlarged scale showing, in plan, the eccentric and the means for actuating the same; and

Fig. 7 is a diagrammatic view further illustrating the movement of a dressing diamond in the dressing of a grinding wheel with the mechanism of the present invention.

Reference will now be had to the drawings for a more detailed description of the invention:

10 denotes the drum that contains the dressing mechanism. This drum is suitably mounted in the grinding machine for reciprocatory movement.

The reciprocatory movement of the drum 10 is produced by a cam 12 (Figs. 2 and 3) which is keyed to a shaft 13 that is suitably journaled in the drum. The shaft 13 is driven from a motor 14 which is mounted in the drum. The motor drives a shaft 15 through a suitable coupling 16. This shaft 15 is suitably journaled in the drum and has a worm 17 fastened to it. (Figs. 2 and 5.) The worm 17 meshes with a worm wheel 18 that is secured to a vertical shaft 19 which is also suitably journaled in the drum. Secured to the shaft 19 at its upper end is a worm 20 that meshes with a worm wheel 21 which is fastened to the shaft 13. The portion of the shaft 13 which carries the worm wheel 21 is of reduced diameter as clearly shown in Fig. 2.

A roller or follower 25 engages in the track 26 of the cam 12. This follower is carried by a pin 27 which is secured in a bar 28. The bar 28 is mounted to slide in suitable bearings formed in the drum 10. The rear end of the bar engages a roller 30 which is carried by the free end of a lever 31. This lever is pivoted at 32 in the drum. Motion of the lever 31 is transmitted to a second lever 35 by a plate 36. The plate 36 has rounded ends and engages in recesses 37 and 38, respectively, in the levers 31 and 35. It is held in operative engagement with the two levers 31 and 35 by a coil spring 44 which is connected at opposite ends to the two levers. The lever 35 is pivoted intermediate its ends, as indicated at 39, in a cover plate 40 that is secured by screws 41 to one end of the drum 10. The lower end of the lever 35 carries a roller 42 which engages with a stud 43 that is secured in a relatively fixed part of the machine.

Since the stud 43 is relatively fixed, rotation of the cam 12 will be translated through the bar 28 and the reducing levers 31 and 35 into a rectilinear movement of the drum 10 in its mounting in the machine. Thus, through the mechanism described, it will be seen that as the cam 12 rotates, the drum 10 will be moved longitudinally. The design of levers 31 and 35 and of plate 36 is such that the movement of the drum with respect to the frame of the machine is exactly proportional to the movement of the bar 28 with respect to the drum, but at a slower rate.

The bar 28 slides not only through the bearings provided for it in the drum 10 but also through an opening in a block 45 which is mounted on the bar. Secured to the block 45 at opposite sides of the bar 28, as by means of screws

47, are two guide plates 46 and 46', respectively, (Figs. 1 and 6). The guide-plates have straight guide surfaces 48 and 48', respectively, that are inclined to the direction of movement of the bar 28 and drum 10. The angle of inclination of the guide surfaces 48 and 48' to the direction of movement of the drum is determined by the inclination of the active side surfaces of one grinding wheel, which is to be dressed, to the central plane of the wheel, that is, its plane of rotation. 10

The guide surfaces 48 and 48' engage spherical rollers 50 and 50', respectively. These rollers are secured in arms 52 and 52', respectively. The arms 52 and 52' are secured to rock-shafts 54 and 54', respectively, that are suitably journaled in the drum 10.

Fastened to the front ends of the rock-shafts 54 and 54' are arms 55 and 55', respectively, (Figs. 1 and 4). The arms 55 and 55' carry at their upper ends pins 57 and 57', respectively, which engage plane side surfaces of lugs 58 and 58', respectively. These lugs are secured to or integral with plungers 60 and 60', respectively. The plungers are mounted in alignment in suitable bearings in the drum 10 to slide toward and from one another. They are normally spring-pressed toward one another by coil springs 62 and 62' which are mounted in recesses in the plungers and which engage at one end with plates 63 and 63', respectively, that are secured in the drum. At their adjacent ends, the plungers carry the dressing diamonds D and D' for dressing opposite sides of the grinding wheel W employed on the grinding machine.

The mechanism so far described is of known construction and is such as is employed in the Jones & Lamson machine. It will be seen from the foregoing description that when means is provided for moving the guide plates 46 and 46' with the bar 28, the rollers 50 and 50' will roll on the guide plates. As the drum moves to the left, then, from the position shown in Figs. 1 and 2, the arms 55 and 55' will be rocked to move the diamonds D and D' apart at the same time that they are moved inwardly from the periphery toward the axis of the wheel by the movement of the drum itself.

Secured to the bar 28 at opposite sides of the block 45 are blocks 65 and 66. The blocks 65 may be fastened to the bar by the pin 27. The plates 65 and 66 are spaced apart a distance somewhat greater than the width of the block 45 to permit some travel of the bar 28 relative to the block 45.

There is a stud 68 secured in the block 45. Rotatably mounted on this stud is a spur gear 70. Integral with the gear is an eccentric collar 71. A ring 72, that is provided with an eccentric bore is fitted on this collar 71 and is rotatably adjustable thereon. Ring and collar may be suitably graduated to permit this adjustment to be made precisely.

Secured in the block 66 is a stud 75 on which is mounted the roller 76. This roller is adapted to engage the periphery of the ring 72 when the drum 10 moves to the left from the position shown in Figs. 1 and 2.

The gear 70 meshes with a rack 80 which is secured by set screws 81 to a bracket 82 (Fig. 6). This bracket is fastened in any suitable manner to the interior of the drum. A gib or clip 83 that is secured to or integral with the block 45 assists, also, in holding the rack in position.

The eccentric 72 operates, during movement of the drum 10, to cause a relative displacement to

take place between the guide plates 46 and 46' and the bar 28. This displacement is at a varying rate and, as already stated, varies the lateral position of the dressing diamonds D and D' with the result that the diamonds are not moved in direct proportion to the uniform movement of the drum 10. Hence the diamonds will dress curved profiles on the grinding wheels.

The operation of the dressing mechanism will be understood from the preceding description but may briefly be summed up here. Let us assume that the cam 12 is rotating in such a direction as to move the bar 28 to the left. This will cause the drum 10 to move to the left also from the position shown in Figs. 1 and 2 through operation of the bar 28, lever 31, plate 36, lever 35 and stop 43. Let us assume also that at this time the eccentric 72 is in the position shown in Fig. 6 with its high point in contact with the roller 76. As the drum 10 moves to the left, the diamonds D and D' will be carried to the left with it and will move from the periphery of the grinding wheel W inwardly toward the axis of the wheel. As the bar 28 moves to the left, also, the roller 76 abuts against the peripheral surface of the eccentric 72, moving the block 45 to the left and causing the gear 70 to roll along the relatively stationary rack 80. At the same time the rollers 50 and 50' will roll on the guide surfaces 48 and 48', respectively, of the plates 46 and 46', respectively. Thus, as the diamonds D and D' move inwardly they are also moved apart through operation of the arms 52 and 52', the shafts 54 and 54', arms 55 and 55', pins 57 and 57' and lugs 58 and 58', respectively.

The rotation of the gear 70 is transmitted to the eccentric 72. As the eccentric rotates, from the position shown in Fig. 6, its high point will pass off of the roller 76 and a lower point of the eccentric will come into contact with the roller. Thus, the movement of the block 45 and the guide-plates 46 and 46' will be slightly retarded relative to the movement of the drum 10. This retardation will affect the movement of the rock-shafts 54 and 54' and of the diamonds D and D'. The diamonds will not move laterally in exact proportion to their inward movement. Hence, diamonds D and D' will not travel along straight lines 85 and 85' (Fig. 7) as the drum 10 moves to the left, but will move along curved lines, dressing curved profiles on the grinding wheel W.

When the diamonds have moved far enough inwardly to dress the active surfaces of the grinding wheel for their full height, the direction of movement of the drum 10 is reversed under actuation of the cam 12. Because the block 65 and 66 are spaced apart a greater distance, however, than the width of the block 45, the guide plates 46 and 46' will not immediately partake of the reverse movement. They will remain stationary, after reversal of the drum, until the block 65 engages the block 45. By this time, the diamonds will have moved outwardly toward the periphery of the wheel far enough that they will clear the sides of the wheel. So the diamonds will not dress the wheel on the return movement of the drum.

By adjusting the eccentric ring 72 on the collar 71, the amount of eccentricity of the ring can be varied conveniently from zero to a maximum so as to produce different amounts of profile curvature. The proper timed relation between the angular position of the eccentric in its rotation and the positions of the diamonds in their motions toward the axis of the grinding wheel can be

adjusted by loosening the set-screws 81 and moving the rack 80 to the proper position in the bracket 82.

In the embodiment of the invention illustrated, the member 12 has a circular periphery. It will be apparent, however, that it might have any other suitable shape for producing any required profile shapes on the grinding wheel. It will also be apparent that the roller 76 and eccentric 72 can be transposed, that is, the eccentric 72 and gear 70 might be mounted on the block 66 and the roller placed on the block 45. The general result attained with the mechanism would remain the same.

It will further be understood that the invention may be applied to other types of dressing mechanisms than that illustrated and the present application is intended to cover any variations, uses, or adaptations of the invention following, in general, the principles of the invention and including such departures from the present disclosure as come within known or customary practice in the art to which the invention pertains and as may be applied to the essential features hereinbefore set forth and as fall within the scope of the invention or the limits of the appended claims.

Having thus described our invention, what we claim is:

1. In a dressing mechanism, a dressing tool, means for imparting a straight line movement to the dressing tool in one direction, and means for simultaneously imparting to the tool a second straight line movement in a different direction, the latter means comprising a slideable guide member having a straight guide surface inclined to its direction of sliding movement, means operatively connecting the guide member to the tool to move the tool on movement of the guide member, and means for moving the guide member at a varying velocity.

2. In a dressing mechanism, a dressing tool, and means for simultaneously imparting to the tool two straight line movements in different directions, the means for producing one of said motions comprising a slideable guide member having a straight guide surface inclined to the direction of its sliding movement, means operatively connecting the guide member to the tool to move the tool on movement of the guide member, and means for moving the guide member at a varying ratio to the other motion.

3. In a dressing mechanism, a carrier, a dressing tool mounted on the carrier, means for imparting a straight line movement to the carrier, a guide member slidably mounted in the carrier and having a straight guide surface inclined to the direction of sliding movement of said guide member, means operatively connecting the guide member to the dressing tool to move the dressing tool on movement of the guide member, and means for imparting to the guide member a combined motion of which one component is directly proportional to the movement of the carrier and the other component is at a varying velocity.

4. In a dressing mechanism, a carrier, a dressing tool mounted on the carrier, for movement in a direction inclined to the direction of movement of the carrier, means for imparting a straight line movement to the carrier, a guide member slidably mounted in the carrier and having a straight guide surface inclined to the direction of sliding movement of the guide member, means operatively connecting said guide

- member to the dressing tool to move the dressing tool on movement of the guide member, and means for moving the guide member at a varying velocity during movement of the carrier.
5. In a dressing mechanism, a carrier movable in the general direction of the height of the surface to be dressed, a guide-member movably mounted on the carrier and having a straight guide surface inclined to the path of movement of the carrier, a dressing tool mounted in the carrier, means operatively connecting the guide member to the dressing tool to move the dressing tool laterally in a plane perpendicular to the plane of movement of the carrier on movement of the guide-member relative to the carrier, means for moving the carrier, and means actuated by the movement of the carrier for producing relative movement between the guide-member and the carrier at a varying velocity.
10. In a dressing mechanism, a carrier movable in the general direction of the height of the surface to be dressed, a guide member movably mounted on the carrier and having a straight guide surface inclined to the path of movement of the carrier, a dressing tool mounted on the carrier, means operatively connecting the guide member to the tool to move the tool laterally in a plane perpendicular to the plane of movement of the carrier when the guide-member is moved relative to the carrier, a rotatable cam for moving the guide member relative to the carrier at a varying velocity, means for moving the carrier, and means actuated by the relative movement between the guide member and the carrier for rotating said cam.
15. In a dressing mechanism, a carrier movable in the general direction of the height of the surface to be dressed, a guide member movably mounted on the carrier and having a straight guide surface inclined to the path of movement of the carrier, a dressing tool mounted on the carrier, means operatively connecting the guide member to the tool to move the tool laterally in a plane perpendicular to the plane of movement of the carrier when the guide-member is moved relative to the carrier, a pair of dressing tools mounted in the carrier, means for moving the tools together in one direction, separate mechanisms for moving each of the tools in a direction inclined to the first named direction to vary the distance between the two tools during their first named movement, and a single control means for actuating the two mechanisms at a varying velocity.
20. In a dressing mechanism, a pair of dressing tools mounted so as to dress, respectively, opposite sides of a grinding wheel, means for moving the tools together in one direction, separate mechanisms for moving each of the tools in a direction inclined to the first named direction to vary the distance between the two tools during their first named movement, and a single control means for actuating the two mechanisms at a varying velocity.
25. In mechanism for dressing the side surfaces of a grinding wheel, a carrier movable in the general direction of the height of the surfaces to be dressed, a pair of guide-members movably mounted in the carrier, each of which has a straight guide surface inclined to the direction of movement of the carrier, the guide surfaces of the two guide members being inclined to one another in accordance with the angle between the opposite side surfaces of the wheel to be dressed, a pair of dressing tools mounted in the carrier, means operatively connecting the guide members with the tools to vary the distance between the tools when the guide-members are moved relative to the carrier, means for moving the carrier, and means operative on movement of the guide members relative to the carrier for moving the guide-members relative to the carrier at a varying velocity.
30. In mechanism for dressing the side surfaces of a grinding wheel, a carrier movable in the general direction of the height of the surfaces to be dressed, a pair of guide-members movably mounted in the carrier, each of which has a straight guide surface inclined to the direction of movement of the carrier, the guide surfaces of the two guide members being inclined to one another in accordance with the angle between the opposite side surfaces of the wheel to be dressed, a pair of dressing tools mounted in the carrier, means operatively connecting the guide members with the tools to vary the distance between the tools when the guide-members are moved relative to the carrier, means for moving the carrier, and means operative on movement of the guide members relative to the carrier for moving the guide-members relative to the carrier at a varying velocity.
35. In mechanism for dressing the side surfaces of a grinding wheel, a carrier movable in the general direction of the height of the surfaces to be dressed, a pair of guide-members movably mounted in the carrier, each of which has a straight guide surface inclined to the direction of movement of the carrier, the guide surfaces of the two guide members being inclined to one another in accordance with the angle between the opposite side surfaces of the wheel to be dressed, a pair of dressing tools mounted in the carrier, means operatively connecting the guide members with the tools to vary the distance between the tools when the guide-members are moved relative to the carrier, means for moving the carrier, and means operative on movement of the guide members relative to the carrier for moving the guide-members relative to the carrier at a varying velocity.
